APPARATUS FOR SIZING PHOTOGRAPHIC PAPER

John C. Trahey, Rochester, N. Y., assignor to
 Eastman Kodak Company, Rochester, N. Y., a
 corporation of New Jersey

Application March 27, 1937, Serial No. 133,423

7 Claims. (Cl. 91—46)

This invention relates to paper making, and particularly to apparatus for sizing photographic paper.

One object of my invention is to provide a paper sizing apparatus through which a sheet of paper may pass continuously at the same rate of speed as it passes through the paper making machine. Another object of my invention is to provide an apparatus for sizing paper in which the paper is treated with a mixture of gas and air to prepare it for receiving the sizing solution. Another object of my invention is to provide an apparatus in which steam and hot air may be mixed in various predetermined proportions in order to prepare the paper to receive a predetermined amount of the sizing solution, and other objects will appear from the following specification, the novel features being particularly pointed out in the claims at the end thereof.

20 In my copending application Serial No. 133,422 filed March 27, 1937, for "A method of sizing photographic paper," I have described in detail a method for controlling the quantity of size taken up by the paper as it passes through a bath.

25 This application relates to a preferred apparatus for carrying out this method. Reference is also made to Patent No. 2,059,881, Lane, "Apparatus for sizing photographic paper," November 3, 1936. The present application is for an improvement 20 over the apparatus shown in this patent.

Coming now to the drawing, wherein like reference characters denote like parts throughout:

Fig. 1 is a front elevation of a pretreatment chamber connected to the gas mixer constructed 35 in accordance with and embodying a preferred form of my invention.

Fig. 2 is a side elevation of the apparatus shown in Fig. 1, parts being shown in section for the sake of clearness.

40 Fig. 3 is an enlarged fragmentary detail of the gas mixing aspirator used in the mixing chamber shown in the preceding figures, and

Fig. 4 is a top plan view of the gas chamber showing the connections between the gas mixing 45 chamber and the gas chest in which the paper is treated.

50 My invention consists broadly in moving a sheet of paper through a gas chest and in mixing a condensable and a non-condensable gas and introducing it into the chest to pretreat the paper before it enters the sizing bath. By varying the proportions of the gases, different sizing effects can be obtained.

55 Referring to the drawing, the gas chest is designated broadly as 1. I prefer to form this

chest in two sections 2, which may be separated upon a line 4 through the center of the chest. The two sections may be separated for threading the paper through the machine, and, if desirable, the sections may be held together in any suitable 5 way, as by set screws 2'.

I prefer to provide a roller 6 mounted on suitable brackets extending across the top of the chest, and a second roller 7 mounted on the bottom of the chest. This roller will normally 10 be immersed in the sizing solution 10 which is placed in the sizing bath 11. The paper 5, as indicated in Fig. 2, passes over the roller 6 down between the lips 8, which extend across the top of the gas chest, through the gas chest and out 15 into the size 10, passing around the roller 7. From this roller the paper may pass through the sizing bath around a roller 30, and then out of the bath between the usual squeeze rolls.

In accordance with my invention, I desire to 20 pretreat the paper while it passes through the gas chest 1, by mixing a condensable gas—steam—with a non-condensable gas—air—and by varying the proportions of these two gases, different sizing effects are obtained.

25 It is possible to treat the paper web with steam alone and very satisfactory results can be obtained with this method. However, it has the disadvantage of making it necessary to alter the viscosity of the sizing solution, or alter the 30 amount of steam passed into the gas chest, in order to vary widely the amount of size which may be taken up by the paper.

With the apparatus which I have shown in this application, a very wide range of sizing can be 35 obtained. If the paper is treated with steam alone, the maximum amount of size is taken up by the paper. If the paper passes into the size without being treated with steam, the minimum amount of size is taken up by the paper. In 40 this instance, the amount taken up is comparable with the ordinary tub-sizing methods.

45 However, by utilizing steam and air in various proportions, it is possible to vary the amount of size taken up by the paper between the comparatively small amount in tub-sizing and the very large amount which occurs when a considerable quantity of high-pressure steam is used to pretreat the paper.

It is necessary to thoroughly mix the steam and 50 air before it passes into the gas chest, and it is preferable to heat the air so that its temperature will not vary a great deal from the temperature of the steam. To accomplish this, I provide a mixing chamber 18 which, in the present instance, is

in the form of a large pipe in which there is an aspirator 19. This aspirator is fed from a steam pipe 20, so that the nozzle 21 directs a jet of steam through the aspirator 19. The amount of steam admitted to the pipe 20 may be controlled by the valve 25. I have found that entirely successful results can be obtained when the steam is at a pressure of approximately two to four pounds, although, of course, the pressure of the steam can 5 be readily altered within wide limits, providing the other factors which effect sizing are properly adjusted.

Air is admitted to the aspirator through the pipe 24, which surrounds the steam pipe 29, and 15 which is introduced by means of the pipe 22 in which there is a valve 23. The air may be drawn in through an air intake in the form of a box 26 which is preferably equipped with an air filter, such as a glass filter 27, so that all impurities will 20 be removed from the air.

In order to heat the air, it is passed from the intake up through a tubular air heater which may conveniently be formed of a pipe of sufficient 25 diameter to encircle a high-pressure steam pipe 29. Thus, as the air moves upwardly through the air heater 28, the steam in the pipe 29 raises the temperature of the air to that, or nearly that of the steam.

The gas mixer 18 is preferably connected to a 30 T-shaped end 17, each end of which is connected by a flexible pipe 16 to a header 15. From this header a series of pipes 13 having perforated distributing heads 13' lead into the gas chest. Each of these leaders is controlled by a valve 14, so that, 35 if desired, the amount of gas admitted to one side of the chest may be made smaller or made greater than the amount introduced to the opposite side of the chest. Of course, since it is desirable to have the mixed gases moving at a comparatively 40 high speed, the gases will be mixed pretty thoroughly in the chest, whether or not the headers are separately controlled but, nevertheless, it is desirable to have the valves 14 for at least an initial adjustment of the apparatus.

In setting this apparatus in operation, the paper 45 is first threaded through the gas chest after being passed around the rollers 6 and 7. It should be noted that the two sections of the gas chest may fit comparatively loosely together because it is 50 desirable to have the gases flow rapidly through the chest. Thus, the lips 8 alone may be spaced apart some distance—such as a quarter of an inch—or the lips, as well as the side edges 4 of the chest may be also spaced apart. It is probable 55 that the fast moving gas drives out all of the air in the interstices of the paper sheet so that the air is replaced by the mixed gases. As soon as this sheet passes into the sizing bath, the mixed gases are replaced by the size. Thus, the gases in the 60 sheet, as it passes into the size bath, control the amount of sizing which the sheet will take up.

As above explained, if steam alone is used, so that substantially all of the air is driven out of the interstices of the sheet, a very large amount of 65 sizing is taken up by the sheet. This is very desirable for some types of paper, but, of course, it is comparatively expensive. There are certain types of paper in which less sizing can be used to advantage, so that in accordance with the present 70 invention, the amount of sizing can be reduced by mixing air with the gas. As soon as the paper has been threaded and the machine has been started, the valve 25 is open to admit steam and the valve 23 may be partially opened to admit some air. 75 As the first part of the paper web is sized, small

samples can be torn or punched from the paper, and these samples can be tested to determine their moisture content, this indicating the amount of size taken up by the paper. If the amount of size required should be indicated by a 35% moisture 5 content and it is found that the tests indicate the paper only has a 30% moisture content, the amount of air introduced may be decreased by closing the valve 23 slightly more than its setting. This will reduce the amount of air drawn in by the 10 aspirator, and as the amount of steam increases, the paper will take up more of the sizing solution.

With this apparatus it has generally been found possible to control the size within wide limits, by 15 allowing the valve 25 to always remain in the same position and by adjusting only the valve 23. However, it may sometimes become necessary to adjust both of these valves to get the desired effect with different grades and types of paper web.

I have also found it possible to keep the viscosity 20 of the sizing solution at substantially the same point for large varieties of sizing effects, as, for example to use 35 pounds of size to 100 gallons of water. When the sizing bath is kept uniform and the amount of steam admitted to the gas chest is 25 kept uniform, it is a very simple matter for even an inexperienced operator to control the amount of size to be taken up by the paper.

What I claim as my invention and desire to be secured by Letters Patent of the United 30 States is:

1. An apparatus for sizing paper comprising in combination, a tank adapted to contain sizing solution, a gas chest having a paper inlet above and a paper exit below the surface of the size, 35 a gas inlet to the chest, a source of steam connected to the chest, a source of air connected to the chest, means included in the steam and air connections for initially mixing the gases before said gases are passed into the chest. 40

2. An apparatus for sizing paper comprising in combination, a tank adapted to contain sizing solution, a gas chest having a paper inlet above and a paper exit below the surface of the size, 45 a gas inlet to the chest, a source of steam and a source of hot air connected to the gas inlet, a mixing chamber including an aspirator for mixing the two gases, valves for controlling the flow of the two gases, said gas inlet being adapted to pass the mixed gases to the chest. 50

3. An apparatus for sizing paper comprising in combination, a tank adapted to contain sizing solution, a gas chest having a paper inlet above and a paper exit below the surface of the size, 55 a gas inlet to the chest, a source of steam and a source of hot air connected to the gas inlet, a mixing chamber including an aspirator for mixing the two gases, valves for controlling the flow of the two gases, said gas inlet being adapted to pass the mixed gases to the chest, and a plurality of distributing heads for the gas inlet to evenly distribute the mixed gases inside of the chest. 60

4. An apparatus for sizing paper comprising in combination, a tank adapted to contain sizing 65 solution, a gas chest having a paper inlet above and a paper exit below the surface of the size, a gas inlet to the chest, a source of steam and a source of hot air connected to the gas inlet, a mixing chamber including an aspirator for mixing the two gases, valves for controlling the flow of the two gases, said gas inlet being adapted to 70 pass the mixed gases to the chest, and a plurality of distributing heads for the gas inlet to evenly distribute the mixed gases inside of the 75

chest, and a separate valve controlling the mixed gases passing through each distributing head.

5. An apparatus for sizing paper comprising in combination, a tank adapted to contain sizing solution, a gas chest having a paper inlet above and a paper exit below the surface of the sizing solution, a gas inlet to the chest, a gas mixing chamber attached to the inlet, said mixing chamber comprising an aspirator and including a nozzle, a steam supply connected to the nozzle, an air supply connected to the mixing chamber near the nozzle, a heater for heating the air, and means for varying the quantity of air supplied to the mixing chamber whereby predetermined mixtures of these gases may be supplied 10 to the gas chamber to treat paper passing therethrough and into the sizing bath.

10. An apparatus for sizing paper comprising in combination, a tank adapted to contain sizing solution, a gas chest having a paper inlet above and a paper exit below the surface of the sizing solution, a gas inlet to the chest, a gas mixing chamber attached to the inlet, said mixing chamber comprising an aspirator and including a nozzle,

zle, a steam supply connected to the nozzle, an air supply connected to the mixing chamber near the nozzle, and means for varying the quantity of air supplied to the mixing chamber, a plurality of valve controlled pipes carried by the 5 inlet to the gas chest whereby the paper may be treated with the gas mixture before entering the sizing solution.

7. An apparatus for sizing paper comprising in combination, a tank adapted to contain sizing 10 solution, a gas chest having a paper inlet above and a paper exit below the surface of the size, a gas inlet to the chest, means for mixing gases connected to the gas inlet to the chest, a source of non-condensable gas and a source of condensable gas, pipes leading to the sources of the gases and to the means for mixing the gases, and means for varying the proportions of the gases admitted to the means for mixing the gases whereby a predetermined mixture of the gases 15 20 may be admitted to the chest for treating paper passing therethrough.

JOHN C. TRAHEY.
